SELECTING CLEARER FOR CLEARING SPUN YARNS

Edouard Doll, Paris, France

Application December 12, 1950, Serial No. 200,359

Claims priority, application France
December 19, 1949

4 Claims. (Cl. 28—64)

One object of the present invention is a device for checking and clearing spun yarns, in order to eliminate defects appearing on said yarns, and spoiling their appearance and mechanical properties, and avoiding at the same time unnecessary stoppage of the machine.

Devices commonly used for clearing yarns comprise a slot with fixed or movable edges through which passes the yarn to be checked, said slot being located in a plane at right angle or at any angle to the path of the yarn. The breadth of the said slot is so adjusted that defects exceeding a given diameter, but whatever their length may be, cannot get through, the yarn being thus stopped and possibly broken if pulled further. In the case of a movable edge slot, the friction of the lump releases, by some mechanical means, the closing of a second member causing the yarn to be stopped by a strong squeezing, such a result increasing the sensitiveness of the apparatus.

The checking principles and operating methods of both devices are technically identical: both stop all defects having a sufficient diameter great enough to squeeze into the slot or to cause operation of the relay, whatever be the length of the defect.

Furthermore complex devices are provided with successive members in order that a defect being missed by one of the said members should be stopped by the following one, whatever be the length of the said defect.

However, if short knots, even of a certain diameter, are not objectionable for the subsequent use of the yarn, it is not the same for defects of the same, or lesser diameter, only slightly exceeding the diameter of the yarn, but having a certain length, or for defects of a larger diameter, even if, in this case, they have only a slight length.

In fact, the criterion is that the apparent surface of the defect (the product of its length by its diameter) should not exceed a maximum value depending upon the quality required for subsequent use of the yarn.

Experience shows that elongated defects, which are the finest ones, frequently are the thinner and have a tendency to be flattened out and to get through the checking slots without the yarn being broken. Consequently the slot must be very tight and accurately adjusted. However, in this latter case, the yarn being constantly pulled through a tight slot, breaks at the slightest or even barely noticeable defect, and, above all, the yarn becomes scratched along its whole length, which spoils greatly its appearance and mechanical properties, and moreover causes a rapid chocking of the yarn clearer, preventing it from operating correctly.

Moreover the accuracy of the adjustment required from any efficient apparatus, whatever the extent to which it has been improved, requires for all existing apparatus, the provision of records resulting from many tests with different yarn diameters, and the use of gauges for adjusting each apparatus. In such cases the adjustment of an apparatus, when starting up a batch of yarn, is a lengthy operation which must be repeated on a large number of apparatus simultaneously used.

All the above-mentioned disadvantages are done away with in using the device according to the invention, viz.:

Unnecessary stoppings by trifling defects,

Impossibility of using modern winders with great linear speeds because of the inertia of the selecting movable members,

Flattening out of elongated defects,
Scratching of the yarn,

2

Operational difficulties in adjusting each apparatus and in determining the best suitable one;

Impossibility of checking the adjustment of an apparatus for any reason in one glance,

5 Clogging of yarn clearers, whence irregular operation of the said clearers.

Each of these disadvantages, separately taken, being enough to make an apparatus inefficient or practically unusable for careful clearing in conditions which are not purely experimental, that is on a production basis.

The principle of the device according to the invention is to use a stopping member having a very high sensitivity and strong squeezing effect, while only passing the yarn through the slot of said member in case a defect appears on the yarn, the normal path of the yarn just passing along the said stopping member, and to have said member preceded by a selecting member, feeling the yarn and shifting it laterally if a defect appears, the degree of said shifting being a function of the diameter of the defect, and the duration of said shifting being a function of the length of the defect, which makes it possible to eliminate the defects according to the criterion of maximum apparent surface hereabove mentioned.

An embodiment of the device according to the invention is described in detail hereafter with reference to the annexed illustrative drawings, in which:

Fig. 1 is a diagrammatic horizontal projection of a simple embodiment, not comprising the adjustment of the slot breadth;

30 Fig. 2 is a cross section along line II—II of Fig. 1;

Fig. 3 is an elevational view of a device comprising an adjustment of the slot breadth;

Fig. 4 is a plan view;

Fig. 5 is a cross-section along line V—V of Fig. 3.

The apparatus diagrammatically shown in Figs. 1 and 2 comprises a base plate 1, two pig-tail thread guides 2, between which the yarn 3 moves from A to B. Between these thread guides the base plate 1 carries a blade 4 oblique with reference to the yarn path and having, in the horizontal plane of said path, a slot 5. The breadth of the slot 5 increases from point 5a, where it slightly exceeds the value of the yarn diameter, to point 5b, where its breadth however slightly exceeds its value at point 5a. A blade 6, carried by the base plate 1 at right angle to direction A, B, is provided, in the horizontal plane of the yarn, with a slot 7 the breadth of which slightly exceeds the diameter of yarn 3. The said blade is located near the end 4b of oblique blade 4, and terminating at point 6b short of axis A, B. A stop 8 limits displacement of the yarn to the side remote from plate 6.

Any defect appearing at oblique blade 4 causes a resistance, which is translated into a force R, which may be divided into a component R₁ at right angle to the plane of the blade, and a component R₂ directed along direction 5a, 5b. Under the effect of component R₂, the yarn is shifted towards 5b, forming an angle to the normal path of the yarn. The normal tension of the yarn in the apparatus, opposing itself to such lateral shifting, creates an effort P, directed along the bisector of the angle formed by the yarn and practically at right angle to axis A, B. Force P may also be divided into a component P₁ at right angle to the plane of the plate and of the same direction as component R₁, to which it is added, and a component P₂ directed along direction 5b, 5a, tending to progressively balance component R₂ of opposite direction. P₁ and P₂ rapidly increase with the displacement of the yarn. The larger increasing defects are shifted under the effect of the difference of forces R₂—P₂ in oblique slot 5, to points nearer and nearer to 5b and they are urged to pass through the said slot under the effect of the sum of forces R₁+P₁. Here, either of the following conditions may happen:

(1) The defect has such a diameter that it passes through oblique blade 4 at a point located between 5a and 5b. At this instant, the yarn having been laterally shifted is engaged in slot 7 of the blade 6. Two possibilities may then appear:

(a) The defect has a length smaller than the distance from X₁ to arc Y, Z, measured on a line passing through X₁ and the exit pig-tail. In this case, after having passed

through oblique slot 5, the yarn will be released and immediately returned to its normal position, before resuming its forward movement; the defect passes outside blade 6 and through the apparatus.

(b) The length of the defect exceeds the distance from its crossing point X_1 through slot 5 of oblique blade 4, to circular arc Y, Z. Then the defect is squeezed in the slot of the stopping member and the yarn breaks.

(2) The defect has such a diameter that it cannot get through oblique slot 5 and reaches point 5b: it is then squeezed into slot 7 of stopping member 6, and the yarn breaks.

Stop 8 limits the displacement of the yarn at its return which is quite rapid, to prevent it from swinging out of the other side of the apparatus, due to its inertia.

Experience shows that, to obtain a good result, the breadth of slot 7 of blade 6 must be slightly smaller than that of oblique slot 5 at point 5a.

The device shown in Figs. 3, 4 and 5 comprises a plate 9, the plane of which comprises the axis or path of the yarn, as determined by thread guides 2'. The said plate carries at its base an extension 10, slidably arranged in a cylinder 11 fixed onto a base plate 12. A screw 13 is screwed into extension 10 and a spring 14 tends to bring plate 9 apart from plate 12. Screw 13 makes it possible to adjust the elevation of plate 9 with reference to plate 12 and consequently, as will be understood hereafter, the breadths of the slots in the selecting plate and in the stopping plate. Head 13a of screw 13 is semi-spherical and a square hole 13b is provided within the said head. This arrangement prevents the adjustment from being changed, except by using a special spanner.

An oblique blade 15 is fixed through a part 16 to a support 17 hinged by means of a shaft 18 to base plate 12. On support 17 is fixed a plate 19 of transparent material such as synthetic resin. A blade 20 is secured to a shaft 21 rotatably mounted in support 17 and a very fine spring 22 tends to maintain the said blade 20 in a slightly inclined position with reference to a plane at right angle to the path of the yarn and in the opposite direction to the direction of travel of the said yarn. Blade 15 and blade 20 cooperate with plate 9 to form the slot-shaped openings 5' and 7'.

Support 17 acts as a cover for the device and defects wedged between the various parts may be cleared off without difficulty. A return spring 23 holds this support in its normal position.

Stop 8' prevents the yarn from being shifted out of the apparatus, due to reaction, following a lateral shifting.

The adjustment of the apparatus is performed without using any gauge and without it being necessary to know the yarn data. For such purpose, the following process takes place:

By acting on screw 13 by means of the adjusting spanner the apparatus is opened beyond the opening sought for and, if needed, to the maximum opening.

The yarn is then started and, by means of the adjusting spanner, the apparatus is closed up to the point where it may be perceived that, due to the squeezing at x' under blade 15, the yarn in its progression through the device becomes shifted in direction z' .

Screw 13 is then slightly loosened to permit the yarn to move under blade 15 in the vicinity of point x' , while maintaining the said yarn slightly vibrating, due to its friction against blade 15. This vibration, easily perceptible in the course of an inspection, is an evidence of the apparatus not being too wide open, which would impair its efficiency. The permanent shift of the yarn in the z' direction reversely indicates too much tightening, which would cause breaks for the slightest defects, the yarn being then, contrarily to the operating principle of the apparatus, constantly engaged under blade 20.

Once thus regulated, the apparatus operates as stated above with reference to the simple apparatus with fixed blades.

While the invention has been described and shown with reference to a single embodiment, it is to be understood that a number of modifications are available to one skilled in the art, within the scope of the following claims and within the spirit of the invention.

What I claim is:

1. A device for checking and clearing yarns and eliminating objectionable defects while remaining with-

out action on non-objectionable defects, comprising spaced yarn guides determining the path of movement of a thread of yarn therebetween, a plate arranged between said guides in a plane parallel to said path and over which the yarn moves between said guides, a blade arranged obliquely of said path, said blade being arranged over said path and extending substantially to one side thereof and being slightly spaced from said plate to define therewith a slot through which the yarn passes, said slot being slightly wider than the diameter of the yarn, and a stopping member arranged substantially perpendicular to said path wholly to said side thereof, said stopping member having one end arranged adjacent said path and its other end projecting beyond the extremity of said blade at said side of said path, said stopping member defining with said plate a slot through which the yarn passes when deflected to said side of said path by said blade.

2. A device for checking and clearing yarns and eliminating objectionable defects while remaining without action on non-objectionable defects, comprising spaced yarn guides determining the path of movement of a thread of yarn therebetween, a plate arranged between said guides in a plane parallel to said path and over which the yarn moves between said guides, a blade arranged obliquely of said path, said blade being arranged over said path and extending substantially to one side thereof and being slightly spaced from said plate to define therewith a slot through which the yarn passes, said slot being slightly wider than the diameter of the yarn, a stopping member arranged substantially perpendicular to said path wholly to said side thereof, said stopping member having one end arranged adjacent said path and its other end projecting beyond the extremity of said blade at said side of said path, said stopping member defining with said plate a slot through which the yarn passes when deflected to said side of said path by said blade, a common support for said blade and said stopping member, said blade and said stopping member being movable away from said plate, and spring means for biasing said blade and said stopping member toward said plate.

3. A device for checking and clearing yarns and eliminating objectionable defects while remaining without action on non-objectionable defects, comprising spaced yarn guides determining the path of movement of a thread of yarn therebetween, a plate arranged between said guides in a plane parallel to said path and over which the yarn moves between said guides, a blade arranged obliquely of said path, said blade being arranged over said path and extending substantially to one side thereof and being slightly spaced from said plate to define therewith a slot through which the yarn passes, said slot being slightly wider than the diameter of the yarn, a stopping member arranged substantially perpendicular to said path wholly to said side thereof, said stopping member having one end arranged adjacent said path and its other end projecting beyond the extremity of said blade at said side of said path, said stopping member defining with said plate a slot through which the yarn passes when deflected to said side of said path by said blade, said stopping member being movable away from said plate, and spring means for biasing said blade and said stopping member toward said plate.

4. A device for checking and clearing yarns and eliminating objectionable defects while remaining without action on non-objectionable defects, comprising spaced yarn guides determining the path of movement of a thread of yarn therebetween, a plate arranged between said guides in a plane parallel to said path and over which the yarn moves between said guides, a blade arranged obliquely of said path, said blade being arranged over said path and extending substantially to one side thereof and being slightly spaced from said plate to define therewith a slot through which the yarn passes, said slot being slightly wider than the diameter of the yarn, a stopping member arranged substantially perpendicular to said path wholly to said side thereof, said stopping member having one end arranged adjacent said path and its other end projecting beyond the extremity of said blade at said side of said path, said stopping member defining with said plate a slot through

which the yarn passes when deflected to said side of said path by said blade, a common support for said blade and said stopping member, said blade and said stopping member being movable away from said plate, spring means for biasing said blade and said stopping member toward said plate, means supporting said plate for linear movement toward and away from said path, means biasing said plate toward said path, and adjust-

able means for limiting movement of said plate toward said path.
